United States Patent

Des. 240,594
Patented July 20, 1976

240,594

BOTTLE

Victor Koenigsberg, Franklin Square, N.Y., assignor to Colgate-Palmolive Company, New York, N.Y.

Filed Mar. 24, 1975, Ser. No. 561,597

Term of patent 14 years

Int. Cl. D9—01

U.S. Cl. D9—143

FIG. 1

FIG. 2

FIG. 3

FIG. 4

FIG. 1 is a front elevation of a bottle embodying my new design, the rear elevation being substantially the same;

FIG. 2 is a right side elevation thereof, the left side elevation being substantially the same;

FIG. 3 is a top plan view thereof; and

FIG. 4 is a bottom plan thereof.

I claim:

The ornamental design for a bottle, as shown and described.
